UNITED STATES PATENT OFFICE.

WILLIAM H. CARTER, OF NEEDHAM HEIGHTS, MASSACHUSETTS, ASSIGNOR TO THE WILLIAM CARTER COMPANY, OF NEEDHAM HEIGHTS, MASSACHUSETTS, A CORPORATION OF MASSACHUSETTS.

STITCH-FINGER FOR SHELL-STITCH MACHINES.

1,172,670.

Specification of Letters Patent. Patented Feb. 22, 1916.

Application filed March 16, 1912. Serial No. 684,146.

To all whom it may concern:

Be it known that I, WILLIAM H. CARTER, a citizen of the United States, and a resident of Needham Heights, in the county of Norfolk and State of Massachusetts, have invented an Improvement in Stitch-Fingers for Shell-Stitch Machines, of which the following description, in connection with the accompanying drawings, is a specification, like characters on the drawings representing like parts.

This invention relates to stitch fingers for shell stitch machines, and is a continuation of and in part a division of my co-pending application Serial No. 617,628, now Patent No. 1,020,944, March 19, 1912.

In order that the principle of the invention may be readily understood, I have disclosed a single embodiment thereof in the accompanying drawings, wherein—

Figure 1 is a side elevation of border forming mechanism embodying my invention; Fig. 2 is a similar view but representing the parts differently positioned; Fig. 3 is a plan view of a portion of the mechanism shown in Fig. 1; Fig. 4 is an edge view of the preferred shape of forming finger about which the loops or stitches are formed; Fig. 5 is a plan view thereof; Fig. 6 is a plan view of one end of a somewhat modified shape of forming finger; and Fig. 7 is a diagrammatic representation indicating the preferred mode of laying the loops or stitches of the border.

Ornamental borders for knitted or other fabrics, such as under-garments, are well known. The patents to Merrow, No. 413,077, October 15, 1889, and No. 414,233, November 5, 1889, clearly disclose the same. The said borders are therein represented as composed of a series of clusters or shells, each consisting of a series of radiating or generally fan-shaped stitches formed by an eye pointed machine needle, a crochet hook or knitting needle, and a hook for a supplemental thread. The clusters or shells are formed in *seriatim*, and the main and supplemental threads thereof are preferably continuous throughout the border. The stitches or loops forming the ribs of the clusters or shells shown in said Merrow patents are

laid along substantially true radial lines and extend in fan shape both to the right and to the left of a median line drawn from the center of the cluster to the edge of the fabric at right angles to said edge.

The object of my invention is to produce a machine made shell or cluster wherein the stitches or loops all tend in the same general direction, that is, toward the right or toward the left as the observer looks toward the fabric; or wherein the threads or loops are so laid that the impression gained by the observer is that of a series of loops extending to the right or to the left as stated. In carrying out my invention I preferably also supply an increased amount of thread in the formation of the loops or stitches, so that the shell instead of being substantially flat as heretofore, is substantially raised from the surface of the fabric or given a puffed appearance.

In carrying out my invention I preferably employ a crochet or over-seaming machine of the general type disclosed in the patent to Merrow, No. 428,508, May 20, 1890, although it is obvious that any suitable means may be employed for producing the border referred to. The mechanism preferably employed includes an eye pointed sewing machine needle, a crochet hook or knitting needle, and a supplemental thread feeding hook.

Referring more particularly to the drawings, the frame of the machine is indicated at 1, the eye pointed sewing machine needle herein represented as vertically reciprocable is indicated at 2, the crochet hook or knitting needle at 3 and the feeding hook for the supplemental thread at 4. These may be positioned as indicated in the said Merrow patents and operated as therein disclosed or in any other suitable manner. The presser foot is indicated at 5 and is preferably spring pressed against the upper face of the fabric and is provided with the customary recess or opening for the passage of the needle 2. The fabric to which the ornamental border is to be applied is introduced at the front of the machine or from the right viewing Fig. 1, and is passed in a step by step manner beneath the presser foot 5, the

under face of which may be recessed from front to rear for the more free reciprocation of the fabric therebeneath.

In order suitably to feed the fabric to which the border is to be applied, I preferably provide a feed slide 6 having a serrated or saw tooth edge 7, the teeth whereof are inclined to the left as indicated in Fig. 1, and an extension 8 having a pin 9 received in a slot 10 of a feed arm 11 pivoted at 12 upon the framing of the machine. Heretofore so far as I am aware, the fabric has been fed in a step by step manner in one direction only, beneath the presser foot, each cluster or shell being formed when the fabric is at rest. In accordance with my invention, however, I impart a step by step forward feeding movement to the fabric and also a comparatively slight rearward movement following each forward movement. This adjunctive rearward movement is for the purpose of positioning the stitches of the shells or clusters in the manner already indicated. It is evident that any suitable means may be employed to this end. Preferably, however, I employ a gear wheel 13 fast upon the shaft 14 and a pinion 15 fast upon a shaft 16 and having thereon an eccentric 17 receiving an eccentric strap 18 of an arm 19 having a slotted pivotal connection 20 with the feed arm 11. In this manner, the feed arm, and consequently the feed slide 6, are reciprocated in both directions. The extent of each forward feeding movement is in this embodiment of my invention materially in excess of the extent of the adjunctive or rearward feeding movement.

Upon a face of the gear 13 I suitably secure or form a cam 21 to under-ride and elevate periodically the roll 22 loose upon a lever 23 pivoted at 23' upon the framing of the machine. The free end of the feed slide 6 rests upon the said roll 22 and the periodic elevation of said roll therefore periodically elevates the feed slide and simultaneously a feeding movement is imparted thereto by the feed arm 11. Within the scope of my invention one or more cams 21 may be employed.

In order to effect the rearward feed of the fabric I provide the gear 13 with a cam 24 having a thin edge or portion 25, which in the rotation of the gear 13 is periodically brought beneath the roller 22 and thereby momentarily elevates the same to effect the rearward feeding of the fabric. The gear 13 is in this embodiment of my invention driven in the direction of the arrow adjacent thereto in Fig. 1 and the relation of the parts is such that when the cam 21 engages and lifts the roller 22, the eccentric 17 is moving the feed slide 6 to the left, viewing Fig. 1. Therefore, the feed slide when elevated into feeding relation to the fabric moves the same by means of its teeth 7 a

suitable distance forward or to the left viewing Fig. 1. The continued rotation of the gear 13 brings the cam 24 beneath the roller 22, thereby again to elevate the feed slide 6. When the feed slide 6 is momentarily elevated by the cam 24 the eccentric 17 has now reached such a position that it imparts a rearward movement or movement to the right to the feed slide 6. Therefore, the momentary engagement of the edge 25 of the cam 24 effects a slight rearward movement of the fabric. As clearly indicated in Figs. 1, 2 and 3, the feed slide 6 is also provided with fabric engaging saw teeth 7 oppositely inclined with respect to the teeth 7, so to effect the rearward feeding movement of the fabric. Therefore the cams 21, 24 act upon the feed slide respectively synchronously with the opposed feeding movements of the eccentric 17.

The shell or cluster formed by the herein disclosed mechanism may obviously have any suitable or desired number of stitches or loops. By an adjustment of the cams co-operating with the feed slide or by the employment of additional cams, I may, for example, form clusters of four, six or eight stitches or more. That form of my invention herein represented is adapted to produce ornamental borders, each shell whereof is composed of eight stitches. If desired, I may provide the edge of the fabric with a double row of shells. In such event, however, the outer overlying row of shells is fashioned as herein described.

At the front of the machine and in the line of feed of the fabric I provide a preferably removable finger 26, shown in detail in Figs. 4 and 5, the edge 27 of which acts as a former about or with respect to which the loops or stitches are laid. This finger is preferably slid into the work face of the machine and may be readily removed. The inner end 28 of said finger extends somewhat to the left of the needle 2, viewing Fig. 1, so that as the stitches are positioned by the needles, they are received by the narrowed inner end of said finger.

In forming the ornamental border, I preferably employ a main or sewing thread 29 carried by the sewing needle 2 and a supplemental thread 30 fed by the hook or guide 4. I also provide the said crochet hook or sewing machine needle 3, to which is imparted a reciprocatory movement above and then beneath the face of the fabric and in substantial parallelism therewith. The needles 2, 3 may be operated in any suitable manner to impart the desired movements thereto.

It will be understood that in the formation of the shell or cluster, each stitch is made up of two lengths or portions of thread constituting a bight or loop. In Fig. 7, the main thread is represented as extend-

- ing from the point 31 of the fabric which constitutes a center from which certain of the stitches of the shell radiate. The hook of the knitting needle 3 is positioned to the 5 left of both threads, and in the continued operation draws them to the right and positions them in the formation of the shell. The needle 3 is then moved to the left beneath the fabric to the lower face thereof, 10 thereby completing one cycle of movement and positioning a single stitch of the shell or cluster. This operation is repeated until a suitable number of stitches to complete the shell are formed. The outer edge of the 15 shell is formed of crocheted loops substantially as indicated in the Merrow patent, No. 414,233, and the supplemental thread preferably enters only into the said crocheted portions of the loops.
- 20 If a double border be desired, then after the fabric has been run once through the machine and a single series of clusters has been formed along or near its edge, the fabric is run again through the machine and the 25 outer series of clusters is formed in or upon the inner series or between it and the extreme edge and extends outward therefrom in the manner herein described.
- Heretofore in the formation of borders 30 composed of a series of shells or clusters, the stitches as laid or during the formation of each shell or cluster slide or are forced by succeeding stitches in the direction of the forward feed of the fabric. Therefore, and 35 assuming the cluster to be formed of eight stitches, it is obvious that the first three or four stitches extend in a forward direction or generally in the direction in which the fabric is fed; that is, toward the left viewing 40 Fig. 1. The final stitches of the shell are extended in a direction opposite to the forward feed of the fabric, because the sewing machine needle which introduces the main sewing thread and the knitting needle do 45 not participate in the forward feeding movement of the fabric, and hence tend to draw the last formed stitches or loops of the shell rearwardly, or so that they radiate toward the right instead of toward the left 50 and in the manner indicated in the Merrow patents, No. 413,077 and No. 414,233. Intermediate stitches or loops of the cluster extend directly outward so that a general fan-shaped effect is produced.
- 55 In carrying out my invention and assuming that the shell or cluster is composed of eight stitches, a certain number of stitches, say three—are laid when the fabric is stationary, that is, after it has been moved into 60 a new position following the formation of the preceding shell or cluster. Thereupon the fabric is moved slightly to the rear and the remaining stitches of the cluster are laid or positioned.
- 65 It will be noted that the edge 32 of the

finger 26, which is the edge overlying the fabric and adjacent the sewing machine needle 2, is substantially straight and is of the full thickness of the finger.

The forward portion of the finger is narrowed as indicated in Fig. 5 and tapers quite abruptly from the outer edge 33 to the inner edge 32 and terminates in a relatively narrow stitch retaining hook 28 having its point bent away from the edge 32, said hook 70 28 preferably lying wholly in the plane of the body of the finger 26. The tapering portion 27 of the forming finger is not straight, but is preferably reversely curved as indicated and is provided with a protruding 75 stitch anchoring shoulder 34, here shown as a substantial swell. The upper face of the finger is preferably beveled or tapered off slightly to the outer edge, so that the said finger will not be interfered with by the other portions of the mechanism, and the narrowed end of the finger is preferably made as thin as possible, as indicated in Fig. 4, so as to give some room for the stitches 80 constituting the clusters or shells. Moreover, the finger is relatively broader than those heretofore employed, in order to compel an increased length of thread to enter into each of the stitches so that the completed shell or cluster is more puffy or elevated than those heretofore formed by machines, and does not lie flat or compressed against the face of the fabric in a manner characteristic of former machine made shells 85 or clusters of ornamental borders.

In Fig. 6, I have illustrated a slightly modified shape of forming finger 35 having a tapered end terminating in a relatively narrow portion 36 and also having a stitch anchoring swell or shoulder 37.

Within the scope of my invention, the forming finger may be shaped as shown in Figs. 5 or 6, or other forms thereof may be employed. Preferably, however, I employ that shape of forming finger represented in 100 Fig. 5, inasmuch as the hook 28 prevents the stitches from slipping off the end of the forming finger until the cluster or shell is completed. Moreover by bending point 28 as indicated, I avoid all danger of the penetration by the point of the stitches pertaining to the adjacent shell or cluster as well as insuring the retention of the stitches upon the forming finger on the return or reverse 105 feeding movement of the fabric.

Referring to the form of forming fingers shown in both Figs. 5 and 6, it will be noted that said fingers are respectively provided with inner and outer edges that are in substantial parallelism throughout the major 110 portion of the length of said fingers, and that the said outer edge of each finger at its forward end has a portion extending forwardly throughout and tapering to the said inner edge, and having thereon an out- 115 120 125 130

wardly extending stitch anchoring shoulder merging at both ends into said forwardly extending portion, said shoulders being indicated respectively at 34 and 37 in Figs. 5 and 6.

As the mechanism herein represented is adjusted, the first few stitches of each shell and preferably the first three stitches are laid when the fabric has been fed forward 10 to a new position immediately following the formation of the preceding cluster or shell. Owing to the described shape of the forming finger, these several stitches practically do not slide forward, but are substantially held 15 in their position as laid by the shoulders 34 or 37. These several stitches radiate from a single center. Thereupon the fabric is moved to the rear slightly as described, so that the succeeding threads of the shell radiate or extend from a new center from 20 which said three stitches were laid. Preferably the first threads of those stitches laid from the second center partially overlie one or more of the threads laid from the first center, so that even though one or more of the threads laid from the first center do radiate very slightly to the left, they are partially concealed by the overlying threads. Practically, however, the first laid threads 25 do not radiate to the left, and the whole general effect of the threads or stitches of the shell is an inclination or curl toward the right.

I do not herein claim the general mechanism for reversely feeding the fabric, inasmuch as such invention is claimed in my Patent No. 1,020,944, but I do herein claim 35 as an article of manufacture the described stitch forming finger, and also that form of finger shown in Figs. 4 and 5 in conjunction with the other parts of the mechanism.

Having thus described one illustrative embodiment of my invention, I desire it to be understood that although specific terms 45 are employed, they are used in a generic and descriptive sense and not for purposes of limitation, the scope of the invention being set forth in the following claims.

Claims.

50 1. A forming finger adapted to receive and form permanently open loops of a shell or cluster border fabric consisting of a relatively broad, elongated plate held in fixed position and having its inner and outer edges in substantial parallelism throughout the major portion of its length, said finger being constructed and arranged to receive said open loops thereabout, said outer edge at its forward end having a portion extending forwardly throughout and tapering to 55 said inner edge and having thereon an outwardly extending stitch-anchoring shoulder merging at both ends into said forwardly extending portion, said tapering portion being of sufficient length to receive there-

about and to support a plurality of open loops constituting a shell or cluster of a border fabric.

2. A forming finger constructed and arranged to receive and form permanently 70 open loops of a shell or cluster border fabric consisting of a relatively broad, elongated plate having the outer edge thereof at its forward end provided with a portion extending forwardly throughout and tapering to the inner edge thereof and having thereon an outwardly extending stitch-anchoring shoulder, merging at both ends into said forwardly extending portion, said tapering portion being of sufficient length to 75 receive thereabout and to support a plurality of open loops constituting a shell or cluster of a border fabric.

3. A forming finger constructed and arranged to receive and form permanently 85 open loops of a shell or cluster border fabric consisting of a relatively broad, elongated plate having its inner and outer edges in substantial parallelism throughout the major portion of its length, said outer edge 90 at its forward end having a tapering portion extending forwardly throughout to said inner edge and there terminating in a relatively narrow point bent away from said inner edge, said tapering portion having 95 an outwardly extending stitch-anchoring shoulder merging at both ends into said forwardly extending portion and being of sufficient length to receive thereabout and to support a plurality of open loops constituting 100 a shell or cluster of a border fabric.

4. Shell or cluster border-forming mechanism for fabrics comprising in combination, a sewing needle, a crochet hook, means for imparting movement thereto, a fixed 105 forming finger having its forward end tapered and terminating in a relatively narrow, stitch-retaining hook, the tapered portion of said finger being of sufficient length to receive thereabout and to support a plurality of open loops constituting a shell or cluster of a border fabric, said parts constituting stitch-forming means for forming 110 stitches in series, means to cause a relative advance of the fabric with respect to said 115 stitch-forming means, and means to cause a relative retrogression of said fabric between the formation and positioning of the first and the last of said series of stitches.

5. Shell or cluster border-forming mechanism for fabrics comprising in combination, a sewing needle, a crochet hook, means for imparting movement thereto, a fixed forming finger having its forward end tapered and terminating in a relatively narrow point, the tapered portion of said finger being of sufficient length to receive thereabout and to support a plurality of open loops constituting a shell or cluster of a border fabric, said parts constituting stitch- 125 130

forming means for forming stitches in series, means to cause a relative advance of the fabric with respect to said stitch-forming means, and means to cause a relative retrogression of said fabric between the formation and positioning of the first and the last of said series of stitches.

In testimony whereof, I have signed my name to this specification, in the presence of two subscribing witnesses.

WILLIAM H. CARTER.
